MAGNETIC CONTROL MECHANISM

Benjamin L. Binford, Chicago, Ill., assignor to
 Magnetrol, Inc., Chicago, Ill., a corporation of
 Illinois

Application October 3, 1946, Serial No. 701,017

2 Claims. (Cl. 200—87)

1

This invention relates to magnetic control mechanism and more particularly to a mechanism employing electrical switches which are operated magnetically in accordance with changes in a condition to be indicated or controlled.

One of the objects of the invention is to provide a magnetic control mechanism which is extremely flexible in use in performing a desired number and sequence of control operations. According to one feature of the invention the mechanism may be built up by assembling a plurality of interfitting control units in a desired combination.

Another object is to provide a magnetic control mechanism including a self-contained switch assembly which can be easily and quickly installed in various types of control installations.

Still another object is to provide a magnetic control mechanism in which a tiltable switch is connected to flexible lead wires in such a way as to minimize flexing of the wires and to maintain a substantial balance of the switch in all positions thereof.

Still another object is to provide a magnetic control mechanism in which a tiltable switch is controlled by a spring which is so arranged as to maintain a substantially constant tilting force on the switch in all positions thereof.

The above and other objects and advantages of the invention will be more readily apparent from the following description when read in connection with the accompanying drawing, in which—

Figure 1 is a vertical section with parts in elevation of a control installation embodying the invention; and

Figures 2, 3, and 4 are top, plan, side, and end elevations, respectively, of a switch unit embodying the invention.

As shown in Figure 1, the installation is adapted to indicate or control the level of liquid in a boiler, tank or the like and comprises a level chamber 10 having top and bottom connections through which it may be connected to the tank or boiler so that the level in the chamber will be the same as that in the tank or boiler. The chamber 10 is closed at its top by a cover 11 formed with a central threaded opening for mounting of the control unit. A float 12 is mounted in the chamber and is connected to an elongated magnetic armature 13 to move the armature in accordance with level changes.

The magnetic control mechanism comprises a base having a central hub portion 14 which is adapted to be fixedly threaded into the opening 15

2

in the cover 11. The hub portion 14 rotatably supports a base plate 15 which may be held in adjusted position on the hub by a set screw 16. The base plate 15 is formed with a threaded opening 17 at one side for connection with an electrical conduit and can be rotated to bring the conduit and the wires therein into the base plate at any convenient position.

The hub 14 fixedly carries a nonmagnetic tube 18 which may be formed of brass or the like. As shown, the tube extends up through the base to terminate in a closed upper end and opens at its lower end into the chamber 10. When the base is assembled on the chamber, the armature 13 fits loosely into the tube for vertical sliding movement therein as the float rises and falls.

The tube 18 is adapted to carry one or more switch units, as more particularly shown in Figures 2 to 4. Each of the units comprises a generally rectangular non-magnetic frame having an end portion 21 which is integral with a side wall 22. At its lower edge the wall 22 is formed with a downwardly extending skirt portion 23 which is offset outward from the upper part of the wall and which has an open bottomed notch 24 therein. At its upper edge the wall 22 is notched or offset as indicated at 25 for a purpose to appear later. The opposite site of the frame, as shown at 26, is connected by riveting or the like to the end wall 21 and is relatively narrow. At the opposite end of the frame the wall 26 is bent over to form a stop finger or arm 27.

Within the central part of the frame there is provided a split mounting block 28 adapted to be drawn together by a screw 29 and of a size to receive the tube 18. In mounting the unit on the tube, the block 28 can be slipped over the tube and moved to the desired level, and the screw 29 can then be tightened to hold the unit in position on the tube. Preferably the lowermost unit is closed at its bottom by a non-magnetic plate 31 fitting over the tube and held at the desired elevation by a spacer 32.

At one end the switch unit carries an insulating contact block 33 provided with a plurality of terminals for connection to the cable and to the switches as described hereinafter. The contact block may be separated by an insulating plate 34 which extends beyond the rectangular outline of the frame and is formed with notches, as best seen in Figure 4, for the flexible leads. At the opposite end the frame rotatably supports an axle 35 which carries a downwardly extending arm 36. At its lower end the arm 36 carries a permanent magnet 37 which is adapted

to move toward the tube 18 when attracted by the armature and which normally occupies a position spaced from the tube, as illustrated. Movement of the magnet away from the tube may be limited by engagement of the arm 36 with the stop finger 27.

The arm is formed with a bracket extension 38 which projects beyond the side 22 of the frame to carry a switch. According to one feature of the invention the switch is carried by a supporting plate 39 pivoted on the bracket 38 and adjustable relative thereto through an adjusting screw 41. In this way the position of the switch can initially be set for any given installation to compensate for slight angularity of the tube 18 with respect to the vertical and to insure proper opening and closing of the switch.

As shown the mechanism embodies tiltable mercury type switches 42 which may be either single or double throw switches, as desired. The switches are supported by supporting clamps 43 carried by the plate 39 and preferably lying above the pivotal axis of the arm, the bracket and the plate. With this construction the entire arm, bracket and plate assembly may be balanced about the pivotal axis to provide for easy and constant operation at all times.

To turn the arm, bracket and plate assembly to the position shown in which the magnet is spaced from the tube, a spring 44 is provided. According to the present invention a relatively long tension spring is employed connected at one end to a finger on the side 22 of the frame and at its opposite end to the plate 39. The connections are so located that as the magnet moves away from the tube toward the position shown, the spring approaches a line through the finger and the pivotal axis of the arm, bracket and plate assembly. As this assembly is turned clockwise to move the magnet toward the tube, as seen in Figure 3, the spring acts through an increasing moment arm to become increasingly effective. Therefore, the tilting forces exerted on the assembly by the spring varies for each position of the magnet in such a manner that the total tilting force on the assembly is substantially constant throughout the full range of movement. Thus when the magnet is remote from the tube and its attraction for the armature is at a minimum, assuming the armature to be in the field of the magnet, the moment produced by the spring on the arm 36 and bracket 39 is at a minimum. Similarly when the magnet is adjacent the tube and its magnetic attraction is maximum the spring moment is maximum. With this construction, a substantially constant and uniform tilting force is produced in one direction or the other depending upon whether or not the armature 13 is in the field of the magnet to provide a uniform and reliable operation substantially insensitive to minor unbalance or vibration.

The switch 42, when installed in the brackets 43, is adapted to be connected to the terminal block 33 by flexible leads 45, as shown in Figure 1. As illustrated in this figure, the switch is a double throw switch requiring three leads. As shown, the leads connect to the switch at points lying on a line crossing the pivotal axis of the assembly and symmetrically spaced about the pivotal axis. With this construction, each of the leads is of a slightly different length so that the connections cannot be confused. Furthermore, the leads extend from the switch generally parallel to the line on which their points of connection to the switch lie. This arrangement involves

minimum flexing of the leads during tilting of the switch and maintains the weight and resistance to flexure of the leads balanced about the pivotal axis. Operation of the mechanism is, therefore, not interfered with by the leads.

In installing a switch mechanism embodying the invention, one or more switch units may be mounted on a single tube 18 at points spaced along the length thereof to perform different indicating or control operations at different points in the travel of the float. According to one feature of the invention, the frames of the switch units are so formed that they will interfit and can be mounted on the same tube relatively close together in making up an assembly. As shown in Figure 1, when the units are so stacked, the positions of alternate units are reversed with respect to each other. In this position the lower edge of the side wall 26 of the upper unit fits into the notched or cut away portion 25 of the unit beneath it while the offset skirt 23 of the upper unit fits over the wall 26 of the unit beneath it. The notch 24 is provided to receive the pivot support carried by the wall 26 of the lower unit so that the units can be stacked relatively close together and will interfit without interference with desired movement of the parts. When the switch units are assembled on the tube, they may be connected with cable wires brought in through the opening 17 in the base plate and which extend up around the sides of the units. The cable wires may be brought up along side the terminal blocks 33 and may be held in the desired location by flanges 46 formed on the end walls 21 of the frames which engage the cable wires to hold them in positions where they will not interfere with proper operation of the switch mechanisms. The entire assembly may be covered by a cup-shaped cover 47 fitting against the base plate 15 and secured by a screw 48 threaded into the upper end of the tube 18. When the cover 47 is installed, it preferably fits relatively closely against the flanges 46 positively to confine the cable wires against tangling.

While one embodiment of the invention has been shown and described in detail herein, it will be understood that it is illustrative only and is not intended as a definition of the scope of the invention, reference being had for this purpose to the appended claims.

What is claimed is:

1. Magnetic control mechanism comprising a non-magnetic frame having a terminal block at one end and having one side formed with an offset skirt to fit over the other side of an underlying mechanism when the frames are stacked in reverse position, means in the central part of the frame to fit over and secure the frame to a tube, an arm pivoted at the other end of the frame, a magnet carried by the free end of the arm for movement toward and away from the tube, a bracket connected to the arm overlying one side of the frame, a switch carried by the bracket, and flexible connections from the terminal block to the switch.

2. Magnetic control mechanism comprising a non-magnetic frame, means on the frame to receive a tube to secure the frame to the tube, an arm pivoted on the frame about an axis transverse to the tube length, a magnet carried by the free end of the arm for movement toward and away from the tube, a bracket connected to the arm to move therewith, a switch carried by the bracket, and a tension spring connected at one end to the frame and at its other end to the

bracket, the latter connection being made at a point between the pivotal axis and the point of connection of the spring to the frame, said point of connection to the bracket being displaced a slight amount to one side of a straight line passing through said axis and the point of connection of the spring to the frame so that the spring will approach said straight line as the magnet moves away from the tube.

BENJAMIN L. BINFORD.
